ABSTRACT

A mandrel for supporting large diameter sanding drums so that they are concentric and balanced. The structure comprises an inner cylinder-like member having heads in each end to which are secured supporting shafts. Slidably surrounding the inner member are metal cylinders having secured to their outer surfaces sleeves of rubber or the like. Spacer washers are interposed between the adjacent ends of the metal cylinders. Means is provided to exert compressive force on the rubber members, from each end of the mandrel, thus to cause the rubber sleeves to distort radially, frictionally securing the sanding drum to the mandrel.

FIG. 2

MANDREL FOR SANDING DRUMS

This invention relates to improved mandrels for mounting sanding drums such as are commonly used in the woodworking arts.

In the art to which my invention relates it is now customary to use sanding drums which are cylinders of relatively thin steel or the like on the outer surfaces of which carbide particles are copper brazed, thus to provide the abrasive surface. The thickness of the material of these cylinders is on the order of 50/1000 of an inch and the diameters thereof may be on the order of 9 inches and in length from 16 to 60 inches. These dimensions are given merely by way of example and are not intended to be the only sizes of saiding drums with which my invention may be used.

In using these cylinders it is necessary to provide a mandrel which will support them for rotation at fairly high speeds. At such speeds, it is desired that they be concentrically mounted on the supporting mandrel which rotates them. In view of the thin wall sections involved it is difficult to provide a mandrel which will hold these cylinders perfectly concentric and without local bulging of the surface of the same, due to the internal supporting means. Furthermore, the supporting mandrel must be almost perfectly dynamically balanced because these relatively large cylinders are run at considerable speeds, such for instance on the order of 8,000 linear feet per minute.

With all the foregoing problems in mind, my invention contemplates a mandrel for mounting sanding drums of the character indicated which shall embody expandable rubber members which frictionally engage the inner surface of the sanding drum, together with means to expand the external diameter of the members uniformly throughout the length of the mandrel, whereby the sanding drum is supported concentrically, without local bulging.

My invention contemplates the provision of a mandrel of the character designated in which the expandable rubber section which engages the inner surface of the drum is divided, longitudinally, into a plurality of separate, radially expandable rubber sections or sleeves.

My invention further contemplates a mandrel of the character designated which, when the axially aligned separate resilient sleeves are put under compressive force, the pressure exerted on the endmost ones is transmitted in turn to the innermost ones, substantially evenly, without overstressing the resilient material in any of their local areas, such for instance adjacent the ends where the force is applied and without undersressing the material, for instance at the center, namely, the place along the length of the mandrel farthest removed from the place of application of the force.

Briefly, my invention contemplates a mandrel for sanding drums of the character indicated comprising central supporting heads about which is placed a cylinder or shell of steel or the like. Axially disposed shafts project outwardly from the heads. Mounted for axial sliding movement upon the inner shell just described is a plurality of individual, separate, relatively short cylinders or sleeves of metal such as aluminum. On the outer surfaces of said sleeves are bonded cylinders of elastomeric material such as rubber or one of the synthetic rubbers. Interposed between each of these aluminum-rubber units is a washer, the washers being reduced in

thickness in those radial areas thereof which are adjacent the ends of the aluminum cylinders. The shafts supporting the mandrel have threaded sections to receive nuts. Interposed between the nuts and the outermost ones of the aluminum-rubber units is a spacer washer adapted to slide up in the ends of the sleeve, into contact with the ends of the rubber cylinders at the ends of the mandrel and to exert pressure on the endmost ones of the rubber bodies when the nuts are drawn up. The pressure exerted on the rubber by these washers in turn is exerted on the outer radial portions of the spacer washers between the aluminum-rubber units which in turn transmits this pressure to the next rubber unit, and so forth. The aluminum sleeves to which the rubber sections are bonded are free to move toward each other in response to the endwise pressure, as permitted by the reduced thickness of the spacer washers. Thus, with the sleeve in place about my improved mandrel, the nuts are run up and the rubber sections are expanded equally, evenly and quite accurately in a radial or outward direction, thus to engage and support the sanding drum from its inner surfaces. The parts are so dimensioned that when in relaxed condition the spacer washers are slightly greater in diameter than the surface of the rubber sleeves so that when the sanding cylinder is moved axially of the mandrel it slides on the peripheries of the washers rather than on the rubber, facilitating the slipping of the same on or off the mandrel. As an added feature I propose to provide a shoulder on the inner steel cylinder, at the longitudinal midpoint thereof against which the innermost ones of the aluminum cylinders engage, upon full compression of the resilient material thereby to transmit the force from a given take-up nut only one-half the length of the mandrel.

Apparatus illustrating features of my invention is shown in the accompanying drawing, forming a part of this application, in which:

FIG. 1 is a side elevational view of my improved mandrel with a sanding drum thereon, the supporting shafts being broken away and in section;

FIG. 2 is an enlarged detail sectional view taken generally along line 2-2 of FIG. 1, the thickness of the shell of the sanding drum being greatly exaggerated;

FIG. 3 is an enlarged detail sectional view taken generally along line 3-3 of FIG. 1; and,

FIG. 4 is a fragmental detail sectional view corresponding to a portion of FIG. 2 and showing the mandrel in relaxed position, that is, in position for the sanding drum to be removed.

Referring now to the drawings for a better understanding of my invention I illustrate the same as being adapted to receive and rotate a sanding drum 10. This sanding drum may embody a relatively thin shell, made of steel, on the order of 50/1000 of an inch in thickness to the outer surface of which are copper brazed abrasive particles. It is the function of my invention to permit this shell to be assembled about the mandrel, whereby upon running in on the clamping mechanisms the rubber members expand radially, thus frictionally to secure the drum to the mandrel for rotation during sanding.

My improved mandrel comprises generally an inner cylindrical member 11 which has heads 12 and 13 secured therein as by welding. Secured to the heads 12 and 13 are shafts 14 and 16, having threaded sections 14a and 16a and reduced sections 14b and 16b passing

through bearings, not shown, and one of which may be a driving shaft.

Slidably mounted on the exterior surface of the cylinder-like supporting member 11 are metal cylinders 17. In view of the fact that these are all duplicates, a description of one will suffice for all. First, each of the metal cylinders 17 carries sleeves 18 of elastomeric material such as rubber. Preferably, this rubber is vulcanized to the outer surfaces of the sleeves 17. As best shown in FIG. 4 when in relaxed condition the rubber members are slightly longer, axially, than the sleeves 17. This is for a purpose later to appear.

Spaced between each of the units comprising the members 17-18 is a spacer washer 19. These washers 19 have axially reduced or thinned sections 19a of a radial extent to permit the metallic sleeves 17 to be pressed thereagainst as shown in FIG. 2, which is the position of the parts with the sanding sleeve secured in place. Radially outwardly of the thinner sections 19a the washers 19 are thickened, axially, as shown and it is these thickened sections which are engaged by the rubber members when the compressive forces are placed on the endmost rubber members 18.

In order to prevent members 17 and rubber members 18 carried thereby from rotating relative to the supporting cylinder-like member 11, I provide a keyway 21 in the outer surface of the member 11 and similar keyways 22 in each of the members 17. As shown in FIG. 2 this keyway is interrupted longitudinally of the cylinder-like member 11 by a radial shoulder 23. Keys 24 are placed in the keyway sections so as to lock the members 17-18 against rotation.

Slidably mounted on the ends of the cylinder-like member 11 are compression washers 26 and 27, so dimensioned as to slide freely up into the ends of the sanding drum 10. Furthermore, these members have annular pads 26a and 27a respectively which are adapted to engage the rubber members 18. Nuts 28 and 29 are provided for threaded engagement with the respective threaded sections 14a and 16a and these may have tool seats 28a and 29a to receive a spanner wrench or the like.

It will be noted from FIG. 4 that when in relaxed condition, that is, when the nuts 28 and 29 are screwed away from the ends of the mandrel, the washers 19 are slightly greater in diameter than the diameters of the rubber members 18. Therefore, when removing and adding sleeves the sleeves slide on the outer surfaces of the washers, reducing the friction required to take the sleeves off or put them on.

Preferably, the cylinder-like member 11, the cylinders 17 and the washers 19 are all made of some material which is a good conductor of heat, for instance, aluminum.

From what has been described it is now possible more fully to explain the construction, function and advantages of my invention. Starting with the nuts 28 and 29 backed off sufficiently to let the parts assume the position of FIG. 4, a sanding drum 10 may be slipped over the mandrel, from either end depending, of course, upon taking the supporting shafts out of their bearings or otherwise making the arbor accessible. In sliding onto the mandrel, in view of the fact that the outer diameters of the washers 19 project past the outer diameters of the rubber members 18, the sleeve slides quite easily and friction-free into proper axial position on the mandrel. The nuts 28 and 29 are now run

up until the series of sleeve-rubber members, 17-18, are brought together as shown in FIG. 2, namely, until the metal sleeves 17 come chock-a-block with the thin sections 19a of the washers 19. By this time the rubber members, each of which is slightly longer than its associated member 17, flows outwardly, that is radially, into tight, frictional engagement with the inner surface of the sanding drum 10. In view of the provision of the shoulder 23 it will be seen that each end of the mandrel, insofar as engaging the sleeve 10 is concerned is independent of the other. Furthermore, by using a plurality of the separately formed members 17-18, and permitting the compressive forces of the endmost rubber members 17 to be transmitted to the next one, etc., I have found that local overstressing of the sanding drum 10 is eliminated, thereby avoiding undesirable bulges in its outer sanding surface which would cause grooving or other imperfections in the work being sanded. Still further, the heat dissipation from the working surface of the drum 10 to the rubber and all the other parts is greatly facilitated by making the metal parts of aluminum.

Because the washers 19 are slightly greater, on the order of 20/1000 inch overall, in diameter, than the rubber members 18, when in relaxed position, a sanding drum placed on the mandrel in relaxed condition is substantially centered and substantially balanced. In other words, a relatively small amount of radial displacement of the rubber is required, and this itself makes my improved arbor not only self centering with respect to its sanding drum, but also practically assures dynamic balance of the same.

In view of the foregoing it will be seen that I have devised an improved mandrel for sanding drums and the like. In actual practice my invention has proven to be extremely practical. Instead of using a continuous rubber member, extending from end to end, the individually formed, separate members 17-18 in combination with means to apply compressive force to each end of the series of the same results in even, substantially equally distributed outward pressure on the sanding drum, securely holding it without causing local bulging of the same.

While I have shown my invention in but one form, it will be obvious to those skilled in the art that it is not so limited, but is susceptible of various other changes and modifications without departing from the spirit thereof.

What I claim is:

1. In a mandrel for supporting sanding drums and the like,
  - a. an inner cylinder-like member,
  - b. means supporting said member for powered rotation about its longitudinal axis,
  - c. a plurality of metal cylinders slidably mounted on the outer surface of said member,
  - d. sleeves of elastomeric material surrounding each of said metal cylinders,
  - e. spacer rings having inner sections interposed between the adjacent ends of the metal cylinders and which are a fraction of an inch greater in diameter than the diameters of said sleeves of elastomeric material when the latter are in relaxed condition, and
  - f. means engaging the endmost ones of said elastomeric sleeves and disposed to exert inward, axial pressure thereon, whereby such pressure is trans-

mitted through the endmost elastomeric sleeves to the adjacent spacer ring thence to the next elastomeric sleeve, and so forth, causing the elastomeric sleeves to distort radially, thereby frictionally to engage the inner periphery of a cylindrical sanding drum placed on the mandrel.

2. Apparatus as defined in claim 1 in which said inner cylinder-like member, adjacent its longitudinal center, has a radially extending abutment against which the adjacent ends of the adjacent metal cylinders come to rest when said pressure is exerted, and in which the means to exert said pressure comprises a threaded shaft at each end of the mandrel, and nuts on the shafts disposed when screwed inwardly of the mandrel to exert pressure on the endmost elastomeric sleeves, whereby the series of elastomeric sleeves on either end of the arbor are stressed independently of each other.

3. Apparatus as defined in claim 1 in which there is means to secure the metal cylinders against rotation relative to the inner cylinder-like member.

4. Apparatus as defined in claim 3 in which the means to secure the metal cylinders against rotation

relative to the cylinder-like member comprises axially extending keyways in the outer and inner peripheries of said cylinder-like member and said metal cylinders, respectively, and a key in said keyways.

5. Apparatus as defined in claim 1 in which said elastomeric sleeves are vulcanized to the outer periphery of their associated metal cylinders.

6. Apparatus as defined in claim 1 in which the elastomeric sleeves and spacer washers are so relatively dimensioned that when said pressure is released the outer peripheries of said washers lie outwardly of the outer peripheries of said elastomeric sleeves, whereby a sanding drum being removed from or placed upon the mandrel slides on said spacer washers, out of contact with the elastomeric sleeves.

7. Apparatus as defined in claim 1 in which the diameter of said spacer washers relative to the inner diameter of the sanding drum to be used with the mandrel is such as to substantially center the sanding drum on the mandrel prior to distorting the elastomeric sleeves into frictional engagement with the drum.
